F. J. Hartman.

UNITED STATES PATENT OFFICE.

FREDERIC E. BALDWIN, OF PHILADELPHIA, PENNSYLVANIA.

COLLAPSIBLE OR DEFORMABLE TUBE.

Application filed April 5, 1924. Serial No. 704,369.

To all whom it may concern:

Be it known that I, FREDERIC E. BALDWIN, a citizen of the United States, and a resident of the city of Philadelphia, county 5 of Philadelphia, and State of Pennsylvania, have invented certain new and useful Improvements in Collapsible or Deformable Tubes, of which the following is a specification, reference being had to the accompanying 10 ing drawing.

My invention relates to collapsible or deformable tubes or containers for containing paste materials, such as tooth paste and shaving cream, intended for frequent use 15 in small quantities, the paste material being forced in the desired quantity from the tube through a neck opening by manual pressure upon the body of the tube. A removable and replaceable cap for the neck seals or 20 closes the opening when the tube is not in use.

A principal object of my invention is to provide a collapsible or deformable tube to which the cap is permanently secured where- 25 by the dropping, or misplacement, or loss of the cap after it is removed from the neck are prevented.

Another principal object of my invention is to provide for the manufacture of caps 30 adapted for use on collapsible tubes of this type whereby economy and speed of production over other processes are secured.

A further object of my invention is to provide a novel means for permanently se- 35 curing the cap to the tube.

A further object of my invention is to provide a cap permanently secured to a col- 40 lapsible tube which forms an air-tight seal to the contents of the tube.

A further object of my invention is to provide a collapsible tube with a cap per- 45 manently secured thereto in which the parts may be assembled with minimum labor.

The foregoing as well as various other ob- 45 jects and novel features of construction and arrangement comprehended by my invention will be more fully apparent from the following description of a preferred em- 50 bodiment of the invention taken in connec- tion with the drawings forming a part hereof.

In the said drawings, Figure 1 is a side 55 elevation of a portion of the collapsible or deformable tube with the cap shown se- cured thereto and provided with my device

for permanently retaining or securing the cap to the tube; Fig. 2 is a view similar to Fig. 1 with the cap shown removed from the neck; Fig. 3 is a view in elevation partly in central section of the cap following the moulding operation; Fig. 4 is a view in elevation of the cap and the retaining device in engagement therewith and illustrates the first step in making caps adapted to be per- 60 manently secured to tubes of this type; Fig. 65 5 is a view in elevation of the completed cap with the retaining device in engagement therewith and illustrates the second step; Fig. 6 is a side elevation of the upper por- 70 tion of the collapsible tube, partly in sec- 75 tion, showing a pair of upstruck or exuded lugs upon the body of the tube between which the outer end of the retaining means is secured; Fig. 7 is a plan view of the top of the tube with the cap and retaining de- 75 vice secured thereto and illustrates the third and final step. The same numerals are used to designate corresponding parts in the se- 80 veral figures.

In the drawings, the collapsible tube 1, 80 which may be made of any suitable material such as block tin, comprises a body portion 2 and an exteriorly threaded neck 3. A cap 4, having interior threads 5, is adapted to be threaded onto the neck and forms the 85 closure for the tube. Said cap 4 is provided with a head 6 and a flanged portion 7 at the bottom thereof, both of which are of larger diameter than the shank 8. While the head 6 is shown as circular, it may be 90 of any desired shape provided that a horizontal section thereof is greater than the horizontal section of the shank 8 whereby the removal or disengagement of the re- 95 tainer from the cap is prevented, the flange 7 being of larger diameter than the diameter of the shank 8 and operating to prevent removal or slipping off of the retainer at the bottom of the cap.

My retaining device comprises a piece of 100 suitable wire, one end 9 of which is formed into a ring encircling, wholly or in part, the shank 8 which is endwise movable and rotatable therein to permit the unscrewing of the cap, and the other end of which is bent downwardly from the ring or portion 9 and is formed into a loop or stirrup 10.

Upon the conical top 11 of the tube, pref- 110 erably near the rim thereof and in substan- tially parallel alignment therewith, are a

pair of upstruck or exuded lugs 12—12 which may be preferably formed simultaneously with the molding of the body portion 2, the lugs being so spaced as to permit the 5 loop or stirrup 10 to be dropped easily there-inbetween and the upper ends of the lugs may then be readily forced toward each other until the loop or stirrup 10 is securely retained between the lugs, thus forming a 10 hinge connection for the wire retainer, it being understood that the lugs are so spaced that the loop or stirrup 10 is held somewhat snugly therebetween, being movable, however, about its axis.

15 After the cap 4 has been unscrewed from the neck 3 to the position shown in Fig. 2, the retaining means, carrying the cap 4, may be moved about its hinge and the cap held in any desired position to permit the 20 contents of the tube to be forced from the neck 3 as desired. The frictional engagement between the loop 10 and the lugs 12—12 may be such as to enable the cap to be held at any position in the arc of its movement 25 about the hinge.

In making caps for tubes, a mold having its bottom portion removable is provided and the material from which the cap is formed is placed in the mold; a plunger having a threaded mandrel then is forced downwardly into the mold under heavy pressure, forcing the material into the mold form and as the plunger is withdrawn the threaded portion thereof rotates and unscrews itself 30 from the thread which has been formed in the interior of the shank of the cap. The bottom of the mold is then removed and the finished cap is pushed down and out of the mold. By this method, however, it is impossible to produce a flange on the bottom 35 of the cap and the practice heretofore has been to mold the cap with a shank having an extra thick wall and then cut away with a lathe a portion of the exterior of the shank 40 wall between the ends of the shank, thereby making the middle portion of the shank a groove of less diameter than the end portions thereof. This method of making the caps adapted for use with retaining devices 45 is almost prohibitively expensive. Another method of making caps provided with a groove between a head and a flange upon the lower end portion adapted for this use, is by making them in a suitable mold which 50 opens but this has been found even more expensive than the method just described. A disadvantage common to both of these methods is that the ring of wire must be sprung over the base or head of the cap onto 55 the shank which frequently distorts the wire and is a slow and expensive operation.

In my invention I have provided for a better method for the manufacture of caps adapted to be permanently secured to collapsible tubes. I preferably use block tin as

the material from which the tube and the cap are made and I first form the cap by molding in the shape illustrated in Fig. 3. Upon the cap thus formed I then drop or slip the ring 9 of my retainer over the bottom of the shank, as shown in Fig. 4, and then form a flange 7 on the lower end of the shank by a stamping, spinning or other suitable operation (see Fig. 5), the ring 9 being held against removal from the cap by the head 6 and the flange 7. The cap with the retainer thereto attached is then secured to the tube 1 by dropping the loop 10 between the lugs 12—12, the upper ends of which are then forced toward each other 70 whereby the loop is securely held against removal. By making the engagement between the loop and the lugs fairly snug, the retainer and the cap carried thereby may be held in any point of the arc of its swing 75 about the hinge by reason of the frictional contact between the loop and the lugs. It will be understood, however, that, if desired, the retainer may be attached to the cap by bending it about the cap or by forcing it over the head or flange. While I have shown a pair of lugs by which the retainer is secured to the tube in the manner above described, it will be understood that but one 80 lug may be used if desired and bent upon itself about the loop 10 to form a suitable hinge connection.

While I have herein described and illustrated a preferred embodiment of my invention, it will be understood that the same is capable of numerous modifications in construction, design and arrangement of parts and I therefore do not thereby desire or intend to limit myself specifically to the precise form of invention so illustrated and described as suitable modifications and changes may be made therein if desired without departing from the spirit and scope 100 of the invention as defined in the appended claims.

Having thus described my invention, I claim and desire to protect by Letters Patent of the United States:

1. A method of forming a hinge lug on a collapsible tube having a semi-rigid breast portion which consists in striking up or exuding a pair of closely adjacent lugs on said breast portion, placing the pintle portion of a cap retainer between said lugs and then pinching the upper portions of said lugs together so as to form an eye for said pintle portion.

2. A closure for collapsible tubes having a screw threaded neck, a screw threaded cap adapted to engage said neck, the cap consisting of an enlarged head, a cylindrical depending shank of smaller diameter than the head and of an enlarged portion constituting a flange at the bottom of the shank, a wire retainer encircling the shank and

adapted to move on the shank parallel with the axis of the shank, and a lug on the breast of the tube adapted to be closed over to hold the wire retainer movably secured to the breast of the tube.

3. A closure for collapsible tubes having a screw threaded neck, a screw threaded cap adapted to engage said neck, the cap consisting of an enlarged head, a cylindrical depending shank of smaller diameter than the head and of an enlarged portion constituting a flange at the bottom of the shank, and a wire retainer encircling the shank and adapted to move on the shank parallel

with the axis of the shank, the end of the wire being attached to the container.

4. A method of forming a hinge lug on a collapsible tube having a semi-rigid breast portion which consists in striking up or exuding a lug member on said breast portion, placing the pintle portion of a cap retainer in operative relation to the lug member, and then bending the lug member so as to form an eye for said pintle portion.

In witness whereof I have hereunto set my hand this 4th day of April, 1924.

FREDERIC E. BALDWIN.
